HIGHWAY CROSSING SIGNAL SYSTEM

Ainslie T. Carter, Barcelona, Spain, assignor to
General Railway Signal Company, Rochester,
N. Y.

Application May 15, 1931, Serial No. 537,665

1 Claim. (Cl. 177—329)

This invention relates in general to highway crossing signals for railway use, and has more particular reference to an improved highway crossing signal giving a plurality of different colored aspects flashing at different rates.

In highway crossing protection it is desirable to provide means to arrest the attention of highway traffic in a very certain manner, and furthermore to do this in the most economical manner possible.

With the above and other objects in mind, it is proposed, in accordance with this invention, to provide a two-aspect color light signal at each side of a railway track where it is crossed by a highway; proceed conditions being indicated by one color, and stop conditions by a different color.

It is further proposed to cause the light indications to flash, with the proceed indication flashing at a slower rate than the stop indication, and to have the energized period of the proceed indication shorter than that of the stop indication. This provides a further distinction in addition to the difference in color, between the different aspects, and furthermore economizes in power consumption and in mechanical wear on the various moving parts.

Further objects, purposes and characteristic features will appear as the description progresses, reference being made to the accompanying drawing, showing, merely by way of example, and in no manner whatsoever in a limiting sense, one form which the invention can assume. In the drawing:—

Fig. 1 of the drawing shows, in a wholly diagrammatic manner, one form of the invention.

Fig. 2 is an enlarged view of the signal used in the system.

Referring to the drawing, there is here shown a stretch of single track constituted by track rails 1, separated into insulated track sections C and D by means of insulating joints 2. Each section has connected across one end of it a source of track circuit energy in the form of a battery 3, with a limiting resistance 4 in series therewith.

Connected across the other ends of the track sections C and D are interlocked relays IR¹ and IR² which can be of any usual or desired form, such, for instance, as shown in the application to O. S. Field, Ser. No. 474,958, filed August 13, 1930. If desired, these interlocked relays can be connected up to repeat the operation of usual track relays.

Crossing the railway track is a highway H, and at each side of the highway, adjacent the track, is a highway signal, which can be of any usual or desired form, but is preferably of the form diagrammatically shown, and described in detail in application 470,056 of O. S. Field filed July 23, 1930. Each signal comprises a permanent magnetic field 5, an electro-magnetic armature 6, a spectacle 7 carrying colored roundels R and G, colored respectively red and green, and a light source 8. This light signal has the spectacle 7 biased, in any desired manner, to position the red glass in front of the light source 8, when armature 6 is de-energized, and to position the green glass in front of the light source 8, when armature 6 is energized.

For controlling the flashing of the light sources 8, there is provided a flashing relay FL, which is of the type shown in application 452,666 of O. S. Field, filed May 15, 1930. In the form diagrammatically shown in the drawing, this relay includes a three-legged core 9, with the outer legs carrying series windings 29 and 30, and the middle leg carrying a separate choke winding 14 and copper washers 14'. The relay FL has a pivoted armature 10, for operating contact fingers in a manner to be described below in detail.

For controlling the duration of the energized periods of the light sources 8, there is employed a slow acting means, in the form of a relay SR.

The various parts are shown in the drawing in the positions and conditions existing when neither of the track sections C and D is occupied. With neither track section occupied, the interlocked relays IR¹ and IR² are both energized which results in energizing the armature of each of the light signals, to thereby position the green glass in front of the light source, said armatures being energized through a circuit including one terminal of a source of energy, contact fingers 11 and 12 and front points of the interlocked relays, and wire 13.

With the interlocked relays energized, the choke winding 14 on the center leg of the flashing relay is short-circuited through a circuit including, the contact fingers 15 and 16 and front points of the interlocked relays, whereby to decrease the rate of operation of the flashing relay from the rate existing when the choke winding 14 is on open circuit.

A bell B is provided, which is energized through a circuit which is obvious from the drawing, and includes either of the contact fingers 17 or 18, and their back points, of the interlocked relays; whereby, with the track sections

unoccupied, so that the interlocked relays are energized, the bell is de-energized.

The slow acting relay SR, is shown as energized through a circuit which includes one terminal of a source of energy, contact fingers 19 and 20 and front points of the interlocked relays, wire 21, contact finger 22 and back point of relay FL, and the winding of relay SR.

In the condition of the parts as shown in the drawing, the light sources 8 are de-energized, since their energizing circuits, which include wires 23 and 24 in multiple, wire 25, contact finger 26 and back point of relay SR, wire 27, and contact finger 28 and back point of relay 15 FL, is open at the contact fingers 26 and 28.

As shown in the drawing, the winding 29 of relay FL, is shunted out of its energizing circuit, whereby to cause the flux in the relay core which is holding the armature 10 in the shown position, to die down at a rate dependent upon the inductance in its circuit, or, in other words, at a slower rate with the choke winding 14 closed, than is the case when choke winding 14 is open. The flux produced by the other end winding 25 30 of relay FL, operates to rock armature 10 to its reverse energized position, and thereby shift contact fingers 22 and 28 and the shunt controlling contact fingers 31 and 32.

On contact finger 22 breaking contact with its back point, and contact finger 28 making contact with its back point, the slow release relay SR is de-energized, and after a predetermined interval of time releases its contact finger 26, to thereby complete the energizing circuits for 35 the light sources 8, as traced above. After a predetermined interval, the flashing relay reverses its contacts, to bring them back to the positions shown in the drawing, to thereby pick up relay SR, and break the energizing circuits 40 for the light sources at the contact fingers 26 and 28.

It should be noted that completion of the energizing circuits for the light sources requires not only that the flashing relay FL shall operate, but that the slow release relay SR shall release, and hence the portion of a complete cycle during which each light source is energized, under proceed conditions, is considerably less than one-half of the total time of the cycle, 50 and can be made as short as desired, simply by increasing the release time of relay SR.

Upon one of the track sections C or D becoming occupied, one or the other of the interlocked relays releases its contact fingers, to thereby 55 complete the energizing circuit for the bell B, as is obvious from the drawing, to thus cause the bell to sound.

The release of one of the contact fingers 15 or 16, opens circuits the choke coil 14 of relay 60 FL, to thereby increase the rate of operation of its armature 10 and various contact fingers.

The release of one of the contact fingers 19 or 20, opens the energizing circuit for the slow release relay SR, whereby contact finger 26 of 65 relay SR remains down during danger conditions, to thereby close the energizing circuits for the light sources at this particular point, and make the energization of the light sources dependent solely on flashing relay finger 28.

70 The release of either of the fingers 11 or 12 of the interlocked relays, de-energizes the armatures of the two highway crossing signals, to thereby cause the spectacles 7 to move by gravity, or any other desired means, to position the 75 red color glasses in front of the light sources.

With the track occupied, the flashing relay FL reverses the positions of its contact fingers 22, 28, 31 and 32. The opening and closing of contact finger 22 on its back point, has no effect on relay SR, since this relay is already de-energized by the release of one of the contact fingers 19 or 20.

5 The closing of contact finger 28 of relay FL on its back point, closes the energizing circuits for the light sources 8, and thus causes the signals to flash.

10 It should be noted, in the case of danger conditions, that the flashing relay FL operates at a faster rate, to give a faster flashing, than under proceed conditions, and that the portion of a 15 complete cycle during which the light sources are energized, is greater than in the first case considered where the track sections C and D were unoccupied, since under danger condition, that portion of the time when the light source 20 is de-energized, which is introduced by the slow acting relay SR, is eliminated, so that the light sources are energized all the time that contact finger 28 is closed on its back point.

15 It will thus be seen that the flashing of the 25 green signal is less rapid than is the flashing of the red, and furthermore, that the green signal is energized a smaller portion of the flashing cycle than is the red signal. In as much as proceed conditions will be present the greater portion of the time, the slower flashing of the green signal operates to very greatly reduce the mechanical wear of the various moving parts in the flashing relay FL. Furthermore, since the green signal is displayed the greater portion of the 35 time, a very decided saving in energy consumption is effected by reducing the portion of the 40 flashing cycle during which it is energized. As a result economies are effected both in mechanical wear and power consumption.

40 It is of course obvious that the rates of flashing of the two signals can be varied at will, and the durations of the energization can be varied at will, by varying the choke coil 14, and the 45 release characteristics of the slow release relay SR. In one form, which has been found very satisfactory, the choke winding 14 resulted in 50 decreasing the rate of operation of the flashing relay, when on closed circuit, to approximately one-half of its rate when the winding 14 was open 55 circuited. In this form the relay SR was adjusted to give a duration of energization of the green signal of approximately one-half that of the red signal.

55 It should be noted that the relay SR can be given any desired characteristics, so long as its release time is made less than the time during which contact finger 28 of relay FL remains in contact with its back point, it being clear that if the release time of relay SR is greater than this, no energization of the green signal can occur.

60 If a signal of the wigwag type should be desired, it is obvious that two signals can be supplied at each side of the highway, with the additional signals operated from corresponding 65 front points, as 50 and 51, of relay FL, together with an additional slow release relay, connected to be energized through 50, for controlling the same.

70 The above rather specific description of various forms of devices embodying the present invention, has been given solely by way of illustration, and is not intended, in any manner whatsoever, in a limiting sense. Obviously, this in- 75

vention can assume many different physical forms, and is susceptible of numerous modifications, and all such forms and modifications, are intended to be included by this invention, as 5 come within the scope of the appended claim.

Having described my invention, I now claim:—

In a signal system, in combination, a plural aspect light signal having a light source, automatic means for determining the aspect displayed, a flashing relay having means to cause

its armature to intermittently pick up and release a choke winding on the flashing relay to vary its rate of operation, a slow release relay having an energizing circuit controlled by the flashing relay, and an energizing circuit for the 5 light source including a back point of the slow release relay and a contact finger and point of the flashing relay.
